(57) **CLAIM**

The ornamental design for a contact lens blister package, as shown and described.

DESCRIPTION

FIG. 1 is a top perspective view of a contact lens blister package showing our new design;

FIG. 2 is a front view thereof;

FIG. 3 is a back view thereof;

FIG. 4 is a left side view thereof;

FIG. 5 is a right side view thereof;

FIG. 6 is a top plan view thereof;

FIG. 7 is a bottom plan view thereof;

FIG. 8 is a top perspective view of a second embodiment of the contact lens blister package showing two contact lens blister packages nested together;

FIG. 9 is a front view thereof;

FIG. 10 is a back view thereof;

FIG. 11 is a left side view thereof;

FIG. 12 is a right side view thereof;

FIG. 13 is a top plan view thereof;

FIG. 14 is a bottom plan view thereof;

FIG. 15 is a top perspective view of the contact lens blister package with a cover sheet attached to its top; and,

FIG. 16 is a perspective view of the contact lens blister package with a cover sheet shown in relation to other blister packages in a carton.

The broken line showing of FIGS. 15 and 16 is included for the purpose of illustrating environment and forms no part of the claimed design.
